FIG. 1

FIG. 2

FIG. 3

INVENTOR.
Bernard Raphael Glukes

UNITED STATES PATENT OFFICE

157,859

PACKAGE CARRYING HANDLE

Bernard Raphael Glukes, Los Angeles, Calif.

Application February 19, 1949, Serial No. 950

Term of patent 7 years

(Cl. D17—5)

To all whom it may concern:

Be it known that I, Bernard Raphael Glukes, a citizen of the United States, residing at Los Angeles, in the county of Los Angeles and State of California, have invented a new, original, and ornamental Design for Package Carrying Handles, of which the following is a specification, reference being had to the accompanying drawing, forming part thereof.

Fig. 1 is a front elevational view of a package carrying handle showing my new design.

Fig. 2 is an end elevational view thereof;

Fig. 3 is a perspective view of the same.

I claim:

The ornamental design for a package carrying handle, as shown.
